PRESSING MACHINE CONTROL LOCK

Ernest Davis, Syracuse, N. Y., assignor to The Prosperity Company, Inc., Syracuse, N. Y., a Corporation of New York

Application November 21, 1930, Serial No. 497,194
Renewed November 4, 1932

17 Claims. (Cl. 68—9)

This invention relates to garment or laundry pressing machines and particularly to means for locking the power control means in operated position for the purpose of holding the press 5 closed under pressure.

It is conventional practice in pressing machines, which are operated by pneumatic motors, to employ control valves which are normally in inoperated position and which do not lock in 10 operated position until after the press is closed. With two-hand control means in particular, it is highly important that the operator be required to hold the controls in position until the pressing elements have come together. With many kinds 15 of work it is necessary to hold the press closed for a period of time and it is therefore desirable that the control valves lock in operated position after the press is closed. With valve locking devices which are operated by the press motor, or by some other part of the actuating mechanism, when such part reaches a predetermined 20 position, the controls may be properly locked under certain conditions and lock too soon or not at all under other conditions. For example settling of the padding on the buck, or changes 25 in the thickness of the work, or play in the connections of the actuating mechanism may cause the part which operates the control lock to lock the controls in operated position sooner than 30 safety would dictate.

The principal object of this invention is to provide means for locking the controls of a pressing machine in operated position, and to operate such means from the pressure between the pressing 35 elements so that the locking operation will always occur at the proper time.

A further object of the invention is to provide the valves, which control the operation of a pressing machine motor, with means for locking them in operated position, and to operate such means from relative movement of a part of the actuating mechanism which will occur when the pressing elements come together.

Other objects and advantages of the invention 45 will appear and will be pointed out as the description proceeds.

The invention consists in the novel features and in the combinations and constructions hereinafter set forth and claimed.

In describing this invention reference is had 50 to the accompanying drawings in which like characters designate corresponding parts in all the views.

Figure 1 is a side elevation of a pressing 55 machine to which the invention is applied.

Figure 2 is a section along the line 2—2 of Figure 1.

Figure 3 is a section along the line 3—3 of Figure 2.

Figure 4 is a section along the line 4—4 of 60 Figure 2.

Figure 5 is a schematic showing, mostly in section, of the motor and control valves, together with the means for locking the control valves in operated position. 65

Figure 6 is a schematic showing, partly in section, of a modification of the control means shown in Figure 5.

The invention is designed primarily for use with pressing machines having opening and 70 closing movement of the type which are provided with a pressing head 11 carried by a yoke 12 which is pivotally mounted on a shaft 13 supported from the pressing machine frame 14. The pressing head 11 is movable toward and 75 from a buck 15 to close and open the press. The buck 15 is supported by a neck 16 mounted on the pressing machine frame 14.

The yoke 12 is oscillated about the shaft 13 by conventional actuating mechanism which 80 includes a bell crank 20 pivotally mounted at 21 on the pressing machine frame 14. The bell crank 20 is pivotally connected at 22 with a link 23 which is pivotally connected at 24 with the yoke 12. The link 23 and the upstanding arm of the bell crank 20 form a toggle which is normally held broken by countersprings 25 and 26. The bell crank 20 is operated by a motor 28 which is oscillatably connected at 29 with the pressing machine frame 14 and which has a 85 piston rod 30 pivotally connected at 31 with the bell crank 20. When pressure is applied to the fluid motor 28 the bell crank 20 is rocked in a counter-clockwise direction to straighten the toggle and rock the yoke 12 in a counter-clockwise direction to bring the pressing head 11 into contact with the buck 15. When pressure in the fluid motor 28 is relieved the countersprings 25 and 26 will restore the press to open position. 90

The shaft 13 is mounted in a bearing block 33 and this bearing block 33 is non-rotatably and slidably mounted in a vertical slot 35 formed in the pressing machine frame 14. The downward pressure of the shaft 13 which results 95 from the weight of the yoke 12, and the parts connected therewith, holds the bearing block 33 normally against the lower end of the slot 35. Compression springs 37 are provided between the bearing block 33 and the upper end of the slot 35. These springs may be held against dis- 100

110

placement by lugs 38 formed on the bearing block 33 and at the upper end of the slot 35. These springs 37 make it necessary to apply a greater force to raise the bearing block 33 in the slot 35 than would be necessary to overcome the downward pressure resulting from the weight of the parts only.

When the press is open the bearing block 33 will rest against the lower end of the slot 35 as shown in Figures 2 and 3. When the toggle link 23 exerts an upward pressure against the rearwardly extending arm of the yoke 12, the yoke will pivot about the shaft 13 to bring the pressing head 11 into contact with the buck 15. The upward thrust of the toggle link 23 during this closing movement of the press, does not exert sufficient force to move the bearing block 33 upwardly in the slot 35. The springs 37 are of sufficient strength to prevent upward movement of the bearing block 33 during the initial closing of the press.

When the pressing elements come in contact further upward pressure of the toggle link 23 will cause the yoke 12 to move upwardly about the pressing head 11 as a fulcrum. This movement of the yoke 12 will cause the bearing block 33 to move upwardly in the slot 35 and compress the springs 37. It is this upward movement of the bearing block 33, which does not occur until the pressing elements have come together under pressure, which causes the operation of the valve locking means in a manner presently to be described.

The bearing block 33, slot 35 and spring 37 form a movable mounting for the yoke 12 which normally is stationary. The movable mounting does not move until the jaws come together and pressure begins to be applied therebetween, which movement is utilized to actuate the control valve locking means or the mechanism to hold the control means in operated position. It will be noted that any mounting for any member of the actuating mechanism or any mounting between members of the actuating mechanism, between the motor means 28 and the movable pressing jaw 11, which is normally stationary and moves only when the pressing jaws 11 and 15 come together and pressure begins to be applied therebetween, may be used to operate a control valve locking means. Such equivalent mechanism is contemplated herein.

A connecting member 40 is mounted on the shaft 13 and this connecting member 40 is provided with a link 42 which is pivotally connected at 44 with a lever 45. The lever 45 is oscillatably mounted at 46 on a bracket 47 which is attached to the pressing machine frame 14.

The lever 45 is connected to a stem 49 of a bellows 50. The bellows 50 is mounted in a bellows casing 52. A pipe 54 connects the bellows with the valve locking means described hereinafter.

The link 42 is connected with the connecting member 40 in a resilient manner to allow for some latitude in the adjustment of the operating mechanism. This resilient mounting is obtained by having the link 42 slidably in a cap 56 which is mounted over the end of the connecting member 40. The connecting member 40 is hollow throughout a portion of its length and this hollow portion contains a spring 58 which surrounds the link 42 and is compressed between the cap 56 and an enlarged end portion of the link 42. From the description thus far and the illustration in Figures 3 and 4 it will be apparent

that upward movement of the bearing block 33 in the slot 35 will cause the shaft 13 to move upwardly. This movement of the shaft 13 will raise the connecting member 40 and link 42 which will rock the lever 45 to compress the bellows 50 and cause the liquid in the bellows 50 to be forced through the pipe 54. The liquid thus forced through the pipe 54 acts to lock the control mechanism in operated position in a manner later to be described.

Figure 5 shows the press operating fluid motor 28 and the control means therefor which include push buttons 60 and 62. The push button 60 operates the valve in the valve casing 65. The valve casing 65 contains a normally open exhaust valve 66 which is formed with a stem 67 projecting through the end of the valve casing 65. A rocker arm 69 is pivotally mounted at 70 on a bracket formed on the valve casing 65. Movement of the push button 60 is transmitted through a bell crank 72 to the rocker arm 69 which operates against the valve stem 67 to move the exhaust valve 66 into closed position. The bell crank 72 is pivotally mounted at 73 on the pressing machine frame 14. A spring 75 normally holds the bell crank 72 and push button 60 in inoperative position.

The push button 62 operates the valves in the valve casing 77. This valve casing 77 contains a normally closed intake valve 79 and a normally open exhaust valve 80 which are connected together by a spacer rod 81 so that they operate as a unit. A spring 82 holds the valves 79 and 80 in normal position. The exhaust valve 80 is provided with a valve stem 84 which projects through the end of the valve casing 77 and against which a rocker arm 85 operates to open the intake valve 79 and close the exhaust valve 80. Motion of the push button 62 is transmitted through a bell crank 86 to the rocker arm 85. The bell crank 86 is pivotally mounted at 88 on the pressing machine frame 14. A spring 89 normally holds the bell crank 86 and push button 62 in inoperative position.

Working fluid is supplied to the valve casing 77 through a fluid supply line 90. The valve casing 77 is connected, at a point midway between the valves, by a pipe 92 with a pipe 93 which connects with a cylinder 95 of the fluid motor 28.

The valve casing 65 is connected by a pipe 97 with the pipe 93. Operation of the push button 62 will open the intake valve 79 and permit working fluid to flow from the fluid supply line 90, around the open intake valve 79, through the valve casing 77, and pipes 92 and 93, to the motor 28. In order to build up pressure in the pipes 92 and 93, sufficient to operate the motor 28, it is necessary to operate the push button 60 to close the exhaust valve 66 and prevent the escape of working fluid through the pipe 97. The valve and piping connections, for supplying working fluid to the motor 28, are of the conventional type used on pressing machines having two-hand control.

The valve casings 65 and 77 are provided with diaphragm chambers 100 and 101 respectively. The diaphragm chamber 100 contains a diaphragm 104 which operates against a plunger 105. This plunger 105 extends through the end of the diaphragm chamber 100 and operates against one end of the rocker arm 69. When pressure is applied behind the diaphragm 104, the plunger 105 will be moved against the end of the rocker arm 69 to hold the rocker arm, and

the valve 66 which is operated thereby, in operated position.

The diaphragm chamber 101 contains a diaphragm 107 which operates against a plunger 108. The plunger 108 extends through the end of the diaphragm chamber 101 and when pressure is applied behind the diaphragm 101 the plunger will be moved against one end of the rocker arm 85 to hold the rocker arm, and the valves 73 and 80 operated thereby, in operated position.

Pipes 110 and 112 connect the pipe 54 with the diaphragm chambers 100 and 101 respectively. The bellows 50 and the pipes which communicate with the bellows 50 are preferably filled with liquid such as oil. When the bellows 50 is operated, as previously described, to force liquid through the pipe 54 this liquid will pass through the pipes 110 and 112 to the diaphragm chambers 100 and 101 respectively to operate the diaphragm and plunger of each diaphragm chamber. The bellows 50 is the means which is operable upon movement of the mounting 33, 35 and 37 and which is connected with the diaphragms 104 and 107 or the holding means for actuating the holding means whereby the control means are held in operative position and the press remains closed.

Means are provided for reducing the liquid pressure in the diaphragm chambers 100 and 101 when the operator desires to open the press. This means includes a bellows 115 which is mounted in a casing 116. A lever 118 is pivotally mounted at 119 on a bracket 120 which is formed on the bellows casing 116. One end of the lever 118 contacts with the top of the bellows 115 and a spring 122 normally holds the lever 118 pressed against the bellows 115 so that the bellows will be compressed. A handle 124 is provided at one end of the lever 118 and this handle 124 may be operated to move the lever 118 against the pressure of the spring 122. When the lever 118 is thus moved the pressure on the bellows 115 is relieved and the bellows free to expand.

The bellows 115 is connected with the pipe 112 by a pipe 125.

The operation of the valve locking mechanism shown in Figure 5 is as follows:—

When the operator wishes to close the press he will depress the push buttons 60 and 62 to move the valves in the valve casings 65 and 77 into operated position for supplying working fluid to the motor 28. When the pressing elements come together the bellows 50 will be compressed in the manner previously described. When the bellows 50 is thus compressed liquid, such as oil, will be forced through the pipe 54, and the pipes 110 and 112, to the diaphragm chambers 100 and 101 respectively. The oil thus supplied to the diaphragm chambers 100 and 101 will exert sufficient pressure against the diaphragms to hold the valves in the valve casings 65 and 77 in operated position as previously described. This oil pressure is not sufficient however to expand the bellows 115 against the force of the spring 122.

When the operator wishes to open the press he will move the handle 124 to relieve the pressure of the lever 118 against the bellows 115. When the pressure on the bellows 115 is thus relieved the air pressure against the exhaust valves 66 and 80, together with the pressure of the spring 82, will move the valve stems 67 and 84 into inoperative position, and force the oil in the diaphragm chambers 100 and 101

through the pipes 110, 112 and 125 into the bellows 115.

When the valves in the valve casings 65 and 77 return to normal position working fluid from the motor 28 will exhaust through the pipe 93 and pipes 92 and 97, and past the open exhaust valves 66 and 80. When the pressure in the fluid motor 28 is thus reduced the counter springs 25 and 26 (see Figure 1) will rock the yoke 12 in a clockwise direction and the shaft 13 will move downwardly and the bellows 50 will be again expanded.

Figure 6 shows a modified form of the control mechanism shown in Figure 5. Most of the parts shown in Figure 6 are not in section since they are identical with the corresponding parts in Figure 5. The only difference between the modification shown in Figure 6 and the structure described in connection with Figure 5 is in the means for reducing the oil pressure which holds the valves in operated position.

Working fluid is supplied to the valve casing 77 through the fluid supply line 90 but an orifice 130 is provided in the fluid supply line 90 to limit the rate of flow of working fluid to the valve casing 77.

The pipe 92 is connected by a pipe 132 with a valve casing 135. The valve casing 135 contains an exhaust valve 136 which is normally held in closed position by a spring 137. A handle 138 is provided which operates against a stem 139 of the exhaust valve 136 to move the exhaust valve 136 into open position.

The closing and locking of the press by the modified control mechanism shown in Figure 6 is identical with that described in connection with Figure 5. When the operator wishes to open the press, with the modified control mechanism shown in Figure 6, he will operate the handle 138 to open the exhaust valve 136. When the exhaust valve 136 is thus opened working fluid from the fluid motor 28 will escape through the pipes 93, 92, and 132, faster than working fluid can be supplied to the pipe 92 through the orifice 130 and valve casing 77.

The pressure in the fluid motor 28 is thus reduced and the pressure exerted by the actuating mechanism against the yoke 12 is correspondingly reduced. Due to this reduction in the upward pressure against the yoke 12 and the springs 37 (see Figures 2 and 3) will move the bearing block 33 downwardly into contact with the bottom of the slot 35 and the bellows 50 (see Figure 4) will be again expanded to relieve the oil pressure in the diaphragm chambers 100 and 101. When the oil pressure in the diaphragm chambers 100 and 101 is thus relieved the valves in the valve casings 65 and 77 will be free to return to normal position in the manner previously described.

From the foregoing description it will be apparent that this invention provides novel valve locking means which are economical and efficient and which will not lock the valves in closed position until the pressing elements are in pressing contact. It will be further apparent that the valve locking mechanism is absolutely unaffected by changes in the thickness of the padding on the buck, the thickness of the work between the pressing elements, or the play or adjustment of the actuating mechanism.

What I claim is:

1. In a garment or laundry pressing machine in combination cooperative pressing jaws one of which is movable with respect to the other; op-

- erating mechanism for the movable pressing jaw including a motor; operator operated means to control the supply of working fluid to the motor; and mechanism, controlled by the pressure between the pressing jaws, for locking the fluid supply control means in operated position. 5
2. In a garment or laundry pressing machine in combination cooperative pressing jaws one of which is movable with respect to the other; operating mechanism for the movable pressing jaw; means for holding the operating mechanism in operated position to lock the press closed under pressure; and hydraulic pressure means, controlled by the pressure between the 10 pressing jaws, for operating the means which hold the operating mechanism in operated position to lock the press closed. 15
3. In a garment or laundry pressing machine in combination cooperative pressing jaws one of which is movable with respect to the other; operating mechanism for the movable pressing jaw including a motor; two-hand control mechanism for said motor including a pair of operator operated valve means both of which must 20 be operated to effectively supply working fluid to the motor; and means controlled by the pressure between the pressing jaws for holding said valve means in operated position to lock the press closed under pressure. 25
- 30 4. In a garment or laundry pressing machine in combination cooperative pressing jaws one of which is movable with respect to the other; operating mechanism for the movable pressing jaw including a motor; valve means for controlling the flow of working fluid to the motor; hydraulic pressure mechanism for holding the valve means in operated position; and means operated by the pressure between the pressing jaws to supply liquid to the hydraulic pressure mechanism to 35 operate the same. 40
5. In a garment or laundry pressing machine in combination cooperative pressing jaws one of which is movable with respect to the other; operating mechanism for the movable pressing jaw including a motor; valve means for controlling the flow of working fluid to the motor; hydraulic pressure mechanism for holding the valve means in operated position; means connected to the operating mechanism and operated thereby, when the operating mechanism applies pressure to the pressing jaws, to supply liquid under pressure to the valve holding hydraulic pressure mechanism; and means for releasing the hydraulic pressure so that the valve 50 means may return to inoperative position. 55
6. In a garment or laundry pressing machine in combination cooperative pressing jaws one of which is movable with respect to the other; operating mechanism for the movable pressing jaw including a motor; valve means for controlling the flow of working fluid to the motor; hydraulic pressure mechanism for holding the valve means in operated position; means connected to the operating mechanism and operated thereby, when the operating mechanism applies pressure to the pressing jaws, to supply liquid under pressure to the valve holding hydraulic pressure mechanism; and means for exhausting a portion of the liquid from said 60 hydraulic pressure mechanism to reduce the pressure therein so that the valve means may return to inoperative position. 70
7. In a garment or laundry pressing machine in combination cooperative pressing jaws one of which is movable with respect to the other; 75
- operating mechanism for the movable pressing jaw including a motor; valve means for controlling the flow of working fluid to the motor; hydraulic pressure mechanism for holding the valve means in operated position; means connected to the operating mechanism and operated thereby, when the operating mechanism applies pressure to the pressing jaws, to supply liquid under pressure to the valve holding hydraulic pressure mechanism; and means for reducing the pressure exerted by the operating mechanism against the pressing jaws and thereby relieving the hydraulic pressure on said valve holding mechanism. 80
8. In a garment or laundry pressing machine in combination cooperative pressing jaws one of which is movable with respect to the other; motor means; actuating mechanism between the motor means and the movable pressing jaw; valve means to control the supply of working fluid to the motor means; means urging the valve means into closed position to cut off the supply of working fluid to the motor means; fluid operated mechanism for holding the valve means in operated position; and means connected to the actuating mechanism and operated by pressure from the actuating mechanism to supply fluid to the fluid operated mechanism for holding the valve means in operated position. 90
9. In a garment or laundry pressing machine in combination cooperative pressing jaws one of which is movable with respect to the other; motor means; actuating mechanism between the motor means and the movable pressing jaw; a mounting for one of the members of the actuating mechanism which is normally stationary and movable only when the actuating mechanism transmits pressure to the pressing jaws; valve means to control the supply of working fluid to the motor means; fluid operated mechanism to hold the valve means in operated position to lock the press closed; and means, operated by movement of the actuating member mounting, for supplying fluid to operate the fluid operated mechanism. 100
10. In a garment or laundry pressing machine in combination cooperative pressing jaws one of which is movable with respect to the other; motor means; actuating mechanism between the motor means and the movable pressing jaw; a pivotal mounting for one of the members of the actuating mechanism; a support on which said pivotal mounting is movably mounted, the support being normally stationary and movable only when the actuating mechanism transmits pressure to the pressing jaws; valve means to control the supply of working fluid to the motor; fluid operated mechanism to hold the valve means in operated position; and means operated by movement of the pivotal mounting on its support to supply fluid to the fluid operated means. 110
11. In a garment or laundry pressing machine in combination cooperative pressing jaws one of which is movable with respect to the other; a lever on which the movable pressing jaw is carried; a pivotal mounting for said lever; support means on which said pivotal mounting is movably mounted; mechanism for operating said lever to close the press; control means for said operating mechanism; and means operated by movement of the pivotal mounting relative to its support means, to hold the control means in operated position. 120
12. In a garment or laundry pressing machine 130

- in combination cooperative pressing jaws one of which is movable with respect to the other; operating mechanism for the movable pressing jaw including a motor; valve means to control the supply of working fluid to the motor; means normally holding the valve means in position to prevent the effective flow of working fluid to the motor; operator operated devices for moving the valve means into operated position to supply working fluid to the motor; hydraulic pressure means to hold the valve means in operated position; a liquid reservoir collapsible by pressure of the operating mechanism, when the pressing jaws are together under pressure to supply liquid to the hydraulic pressure means; and means operable to withdraw liquid from the hydraulic pressure means to reduce the pressure therein and thereby render said means inoperative to hold the valve means in operated position.

13. In a garment or laundry pressing machine in combination cooperative pressing jaws one of which is movable with respect to the other; operating mechanism for the movable pressing jaw including a motor; valve means to control the supply of working fluid to the motor; means normally holding the valve means in position to prevent the effective flow of working fluid to the motor; operator operated devices for moving the valve means into operated position to supply working fluid to the motor; hydraulic pressure means to hold the valve means in operated position; a liquid reservoir collapsible by pressure of the operating mechanism, when the pressing jaws are together under pressure, to supply liquid to the hydraulic pressure means; and means to reduce the pressure exerted by the operating mechanism against the pressing jaws and thereby relieving the pressure in the hydraulic pressure means to render the same inoperative to hold the valve means in operated position.

14. In a garment or laundry pressing machine in combination cooperative pressing jaws one of which is movable with respect to the other; motor means; actuating mechanism between the motor means and the movable pressing jaw; a mounting for one of the members of the actuating mechanism which is normally stationary and movable only when the actuating mechanism transmits pressure to the pressing jaws; control means operable to supply working fluid to the motor means; manual means connected with the control means; means for holding the control means in operated position; and means operable upon movement of the mounting and connected with the holding means for actuating the latter to hold the press closed.

15. In a garment or laundry pressing machine in combination cooperative pressing jaws one of which is movable with respect to the other; motor means; actuating mechanism between the motor means and the movable pressing jaw; a mounting for one of the members of the actuating mechanism which is normally stationary and movable only when the actuating mechanism transmits pressure to the pressing jaws; control means operable to supply working fluid to the motor means; manual means connected with the control means; means for holding the control means in operated position; means operable upon movement of the mounting and connected with the holding means for actuating the latter to hold the press closed, and means to release the holding means.

16. In a garment or laundry pressing machine in combination cooperative pressing jaws one of which is movable with respect to the other; motor means; actuating mechanism between the motor means and the movable pressing jaw; a mounting for one of the members of the actuating mechanism which is normally stationary and movable only when the actuating mechanism transmits pressure to the pressing jaws; valve means to control the supply of working fluid to the motor means; manual means connected with the valve means for actuating the latter; fluid operated mechanism to hold the valve means in operated position to lock the press closed; and means, operated by movement of the actuating member mounting, for supplying fluid to operate the fluid operated mechanism.

17. In a garment or laundry pressing machine in combination cooperative pressing jaws one of which is movable with respect to the other; motor means; actuating mechanism between the motor means and the movable pressing jaw; a mounting for one of the members of the actuating mechanism which is normally stationary and movable only when the actuating mechanism transmits pressure to the pressing jaws; valve means operable to control the supply of working fluid to the motor means to close the press and to hold the press closed; fluid operated mechanism to hold the valve means in operated position to lock the press closed; and means, operated by movement of the actuating member mounting, for supplying fluid to operate the fluid operated mechanism.

ERNEST DAVIS.
